UNITED STATES PATENT OFFICE.

EDWARD E. CLEMENT, OF WASHINGTON, DISTRICT OF COLUMBIA.

ELECTRICAL CONTACT.

1,027,240.

Specification of Letters Patent. Patented May 21, 1912.

Application filed September 29, 1906. Serial No. 336,738.

To all whom it may concern:

Be it known that I, EDWARD E. CLEMENT, a citizen of the United States, residing at Washington, in the District of Columbia, have invented certain new and useful Improvements in Electrical Contacts, of which the following is a specification, reference being had therein to the accompanying drawing.

10 My invention relates to contact springs and the contact points thereof; especially to the latter and more especially to contact points used upon the springs of relays and other spring switches. In the present use 15 of such springs they are generally constructed of German silver with platinum rivets and disks secured thereto. The excessive cost of platinum and the apparent lack of some cheaper metal which would 20 perform the same function has led up to the present invention.

The invention consists in its simplest form of drawing a wire with a platinum coating thereupon into the requisite size 25 then rolling the wire at stated intervals so as to form constricted portions where the interior metal is practically absent and where the several enlarged portions between the constricted parts can be severed from 30 one another. These portions with their then pointed ends are formed up into rivets as in Figure 3 which are practically inexpensive as compared with the solid platinum rivets now employed for this purpose.

35 My invention is illustrated in the accompanying drawings in which—

Fig. 1 is a longitudinal sectional fragment of the wire as it is drawn before forming. Fig. 2 is a longitudinal section of 40 the wire after being rolled or compressed. Fig. 3 shows a sectional view of the rivet. Fig. 4 shows a side elevation of a contact spring with the rivet in position, and Fig. 5 is a top plan view thereof.

45 In Fig. 1 I show a section of a piece of wire 1 of any suitable material such as German silver, silver or copper which is coated, plated or has drawn thereon a covering of platinum 2. The wire is then rolled 50 or compressed at points marked 3 in any suitable manner to form constricted portions where the base metal 1 is practically absent. This process of course forces the

base metal into the enlarged portions 4 of the wire and somewhat increases its lateral 55 dimensions thereat. The enlarged portions 4 now being separated by the constricted portions 3 are then cut off upon the dotted lines $x-x$ and each separate piece is then formed up as shown in Fig. 3, whereby a 60 head 5 and a shank portion 6 is formed with the base metal 1 inside and the platinum coating 2 upon the outside. This forming also compresses one end of the piece as at 65 7 to form practically a solid platinum point, the metal from within being squeezed or compressed into the shank 6 and the head 5. The rivet is now passed through an aperture 8 in one end of the spring 9 and the extended portion 7 is flattened out to 70 form the disk contact 10 which forms the mate for the pointed head contact 5.

It will be seen from this construction that very little platinum is used and that the cost of the rivet is thereby greatly reduced, 75 thus enabling relays or other switching devices to be manufactured at little cost as compared with the now rather expensive mode of construction. It will also be seen that I may use any sort of metal suitable 80 for a body and that I may also coat or cover the body of base metal in any suitable manner such as plating, rolling or inserting the body within a tube of platinum and then drawing both together. All such modifications are considered to be within the scope 85 and purview of the appended claims.

Having thus described my invention what I claim and desire to secure by Letters Patent is:

1. A rivet comprising a body of base metal, a coating of non-oxidizable metal, and a rivet extension formed of the latter metal.

2. A rivet comprising a head and a shank 95 of base metal, a coating of non-oxidizable metal therefor, and a continuation of the shank formed of said latter metal.

3. In a contact point for circuit changing springs the combination with a shank 100 and a head of base metal, of a covering of non-oxidizable metal for said head and shank and non-oxidizable means forming an extension of said shank, said means forming the flat mate contact and the pointed 105 head.

4. The process of tipping electrical contact springs with precious metal which consists of welding a surface layer of said precious metal upon a body of baser metal, cutting said bimetallic body into cylinders tipped with said precious metal, inserting said cylinders into holes in the electrical contact springs and riveting said cylinders

into close contact with said springs and with the precious metal exposed.

In testimony whereof I affix my signature in presence of two witnesses.

EDWARD E. CLEMENT.
